APPARATUS FOR MAKING BOTTLE CAPS

Charles A. MacCordy, Syracuse, N. Y., assignor
to Sanitary Metal Cap Corporation, Syracuse, N. Y.

Application July 27, 1933, Serial No. 682,474

38 Claims. (Cl. 153—7)

This invention relates to an apparatus for making overall bottle caps in which and by which the cap is formed in one piece, preferably from a sheet of light, strong and durable metal having a high degree of ductility, malleability and tenacity such, for example, as tissue aluminum of about the thickness of "cellophane" or thin tinfoil capable of being easily molded under pressure to the desired form under atmospheric temperatures and of retaining its form under ordinary usage.

The main object is to produce in one operation a bottle cap of this character with a central cup-shaped portion and a marginal skirt portion in which the cup-shaped portion is of slightly less diameter than the interior diameter of the mouth of the bottle while the skirt portion is of slightly greater diameter than that of the head of the bottle so that the cap may easily drop into place upon the bottle by its own weight ready to be sealed thereon by any suitable capping machine in a manner hereinafter described.

Another object is to render the cap self-retaining upon the bottle when applied thereto without extra retaining means.

A further object is to form the overturned rim of the cup-shaped portion with substantially radial ribs and grooves alternating with each other in regular order for reinforcing and expansion purposes.

One of the specific objects is to rumple the skirt in an axial direction about its circumference during its formation so as to render it more pliable and, therefore, more easily expanded and contracted over and upon the mouth of the bottle than would otherwise be possible, the term "rumple" being used in its broadest sense to indicate irregular and relatively fine wrinkles.

Other objects relating to the means for forming the rim corrugations (ribs and grooves) and rumpled skirt will be brought out in the following description.

In the drawings:—

Figure 1 is a top plan of my improved bottle cap.

Figure 2 is a side elevation of the same.

Figure 3 is a vertical sectional view taken on line 3—3, Figure 1.

Figure 4 is an enlarged detail horizontal sectional view of a portion of the skirt of the cap taken on line 4—4, Figure 3.

Figures 5 and 6 are vertical sectional views respectively of the upper and lower sets of dies for forming the cap, a portion of the sheet from

which the cap is to be formed being shown by dotted lines as resting upon the upper face of the lower set of dies, the dies of both sets being shown in their normal open positions.

Figure 7 is an inverted end view of the upper set of dies shown in Figure 5.

Figure 8 is a top plan of the lower set of dies shown in Figure 6.

Figure 9 is an enlarged vertical sectional view of both sets of the dies in their closed cap-forming positions, the cap being shown in section.

Figure 10 is an enlarged detail sectional view taken on line 10—10, Figure 9, showing portions of the adjacent ends of the lower and upper corrugating dies, but more particularly the relation of the cooperative sets of balls for forming the ribs and grooves in the rim of the cup-shaped central portion of the cap.

Figure 11 is an enlarged vertical sectional view of one side of the upper end of the lower die-post and lower end of one side of the upper die in position to form the rim corrugations of the bottle cap together with a portion of the spring ring in position for rumpling the skirt of the cap, a portion of which is also shown in section, the dotted lines indicating the position of the ribs when the cap is finished.

As illustrated more clearly in Figures 1 to 3 inclusive and Figures 9 and 10, the bottle cap is made of extremely thin or tissue aluminum or its equivalent having a high degree of ductility, malleability and tenacity, together with inherent lightness and non-corrodibility and comprises a substantially cylindrical cup-shaped central portion 1 having an overturned rim 2 and a marginal skirt 3, all of which parts are arranged about a common axis representing the axis of the bottle to which the cap is to be applied.

The bottle (not shown) to which the cap is to be applied may be of any well-known construction having the usual inner annular ledge, the rounded rim, enlarged head, and reduced neck.

The cup-shaped portion 1 of the cap is of slightly less diameter than that of the interior of the mouth of the bottle to allow it to readily seat itself therein under its own weight preparatory to sealing the same by any suitable capping machine, and is provided with a substantially flat and horizontal bottom portion 1' disposed in a plane at substantially right angles to the axis and adapted, if necessary, to rest upon the inner annular ledge of the mouth of the bottle.

The rim 2 of the cap is concavo-convex in cross section to conform more or less closely to the

rounded contour of the top of the bottle with which it is adapted to engage.

The skirt portion 3 is of slightly greater diameter than the external periphery of the head of the bottle to enable it to readily pass over and around the same during the capping operation.

The overturned rim 2 is provided with raised ribs 4 and grooves 5 alternating with each other in regular order throughout the circumference 10 of the rim, thereby establishing regular corrugations for reinforcing purposes and also to permit the inner upright side walls of the rim to be expanded into close engagement with the inner periphery of the mouth of the bottle by suitable 15 capping means, not necessary to herein illustrate or describe, because this expansion of the rim of the cap takes place only during the capping operation.

The ribs 4 are relatively narrow as compared 20 with the width of the grooves 5 but are arranged in uniformly spaced relation circumferentially and are of uniform height to stiffen the rim and thereby to hold the bottom portion 1' and skirt portion 3 in more or less fixed concentric relation.

25 The skirt 3 is rumpled or irregularly crinkled axially to enable it to be easily placed over and upon the head of the bottle without material friction therewith and at the same time permitting the lower edges thereof to be easily contracted around the outer periphery of the head and neck of the bottle under comparatively light inward radial pressure on all parts thereof during the capping operation.

The ribs 4 extend substantially radially across 35 the top of the rim 2 and also extend downwardly therefrom along the inner upright side of the rim to points close to but slightly separated from the bottom 1' so that when the cap is applied to the head of the bottle, the upright inner walls of the cup-shaped portion 1 may be expanded by a suitable capping die or plunger tightly against the inner periphery of the mouth of the bottle to effectively prevent the leakage of the contents 40 of the bottle through the joint, leaving the radial portions of the ribs and bottom walls of the 45 grooves 5 in substantially their original positions after having been previously formed.

Specific mechanism is provided for forming the cap as described so that all portions of the cap 50 may be formed in practically one and the same operation.

As illustrated, this cap forming means comprises a lower set of dies mounted in and upon 55 vertically spaced and relatively stationary supporting members 6 and 6', and an upper set of dies mounted in and upon a vertically movable plunger plate 7 adapted to be reciprocated vertically toward and from the upper frame member 6' by any suitable means, not necessary to herein 60 illustrate or describe.

Lower set of dies

The lower set of dies preferably comprises a 65 relatively stationary upright post 8 rigidly mounted upon the lower frame member 6 to extend upwardly therefrom, and for this purpose has its lower end reduced in diameter and tightly secured in an opening 8' in said frame member with its 70 lower end substantially coincident with the lower face thereof.

A clamping screw 9 is screwed from the underside upwardly into a central threaded socket 10 in the lower end of the post 8 and is provided 75 with a washer 11 engaged with the head of the

bolt and with the underside of the frame member 6 to firmly clamp the post to said member against relative axial or angular movement and, if necessary, the post may be locked to the frame member 6 by means of a key 11', as shown in Figure 6. 5

The portion of the post 8 above the frame member 6 is preferably cylindrical and of a diameter corresponding to the internal diameter of the skirt 3 of the cap to be formed on the upper end thereof but somewhat greater than the external diameter of the head of the bottle for a purpose presently described. 10

The upper end face of the post 8 and upper face of the upper frame member 6' are disposed in substantially the same horizontal plane for receiving and supporting the sheet material as A shown by dotted lines in Figure 6 and from which the cap is to be formed, it being understood that the sheet material may be intermittently fed in any suitable manner from a reel or other source 15 of supply across and upon the upper face of the upper frame member 6'. 20

The upper outer annular corner of the post 8 is provided with a multiplicity of relatively small substantially hemispherical sockets 12 arranged in relatively close but uniformly spaced relation circumferentially entirely around the periphery of the post for receiving and supporting a corresponding number of relatively small hardened metal balls or bearing members 13 of the same 25 radius as their respective sockets 12. 30

The diagonally opposite walls of the open sides of the sockets 12 are preferably crimped or swaged against the adjacent portions of their respective balls to firmly hold the latter in operative position against displacement and preferably against relative rotation so that the outer lateral faces of the balls will be substantially coincident with the adjacent portions of the periphery of the post 8, thus providing the upper outer corner of the post 40 with a corresponding number of rounded or spherical bearings around which the skirt 3 of the cap may be bent, in a manner hereinafter more fully explained. 45

The top of the post 8 is provided with a circular recess 16 of somewhat less diameter than the interior diameter of the mouth of the bottle, the lower end of which is slightly enlarged to receive and retain a resilient cushion plate 17 of rubber or equivalent material adapted to rest upon the flat bottom of the recess and against the peripheral walls thereof, as shown in Figures 6 and 9. 50

This recess extends upwardly above the upper face of the cushion 17 a distance substantially equal to the axial depth of the cup-shaped portions of the cap 1 and its internal diameter is substantially equal to the external diameter of said cup-shaped portion so that when the latter is pressed into the upper end of the recess and against the upper face of the cushion 17 in a manner presently described, it will form the central cup of the cap of somewhat less external diameter than the internal diameter of the mouth of the bottle, as shown in Figure 3. 55

The object of the resilient cushion 17 is to facilitate the embossing of the bottom of the cup by embossing characters on the lower face of the upper cup-forming die, hereinafter explained. 60

Provision is made for replacing these cushions from time to time as they become worn and for this purpose, the post 8 is provided with a central lengthwise guide opening 18 extending therethrough and through the clamping screw 9 for receiving an ejector rod 19 which extends down- 70

wardly through the guide opening 18 and below the lower end of the clamping screw 9, the upper end of said ejector rod being enlarged at 20 to normally rest in a reduced extension of the circular recess 16 and against the lower face of the cushion 17 so that when the cushion becomes worn or otherwise impaired it may be expelled from the recess 13 by upward movement of the ejector rod 19.

10 A new cushion may then be inserted from the top downward into and against the bottom of the recess 16 to rest against the upper enlarged end 20 of the ejector stem.

The upper frame member 6' is provided with a circular opening 21 concentric with the axis of the post 8 and of somewhat greater diameter than that of the circular blank from which the cap 1 is to be formed, the upper end of said opening being enlarged for receiving a hardened metal 20 shearing ring 22 which is secured in place by clamping bolts 23 with its upper face in the same plane as that of the frame member 6' as shown in Figures 6 and 9.

The inner diameter of the shearing ring 22 is 25 slightly less than that of the underlying portion of the opening 21 and is of the same diameter at the top as that of the flat blank from which the cap is to be formed.

A tubular clamping member 24 is telescopically 30 mounted upon the periphery of the upper end of the post 8 for relative vertical movement and has its upper end enlarged to the interior diameter of the shearing ring 22 to closely fit therein when in its up position, as shown in Figure 6, 35 said enlargement having its lower end provided with an annular shoulder 25 adapted to engage the underside of the adjacent portion of the ring 22 to limit the upward movement of the tubular clamping member 24.

40 The vertical depth of the annular enlargement on the upper end of the tubular clamping member 24 is somewhat less than that of the ring 22 but is supplemented by an additional hardened metal ring 26 of the same external diameter 45 as the internal diameter of the ring 22 and is secured to the upper face of the tubular clamping member 24 by screws or bolts 26', it being understood that the inner diameter of the ring 26 is equal to the external diameter of the post 50 8, as shown in Figure 6.

A spring 27 is interposed between the enlarged upper end of the clamping member 24 and upper face of the lower frame member 6 around the post 8 for yieldingly holding the clamping member 24 in its uppermost position with its shoulder 25 engaging the underside of the ring 22, as shown in Figure 6.

Upper set of dies

60 The upper set of cap forming dies are mounted upon the plunger member 7 and comprises an inverted cylindrical cup-shaped member 28 having its upper end secured by bolts 29 to the underside of the plunger plate 7 to extend downwardly therefrom in co-axial relation to the post 8, the interior diameter of the lower half of the member 28 being somewhat greater than the external diameter of the skirt 3 of the cap 1 and, therefore, of still greater diameter than the external diameter of the upper end of the post 8 so that when the plunger plate 7 is moved downwardly to its pressing position in the act of forming the skirt 3, the lower end of the member 70 28 will extend around the upper end of the post

in spaced relation thereto, as shown in Figure 9.

The top wall of the member 28 is provided with a central pendant boss 30 extending downwardly therefrom co-axial with the post 8 and of considerably less external diameter than the internal diameter of the outer portions of the member 28 to form an intervening annular chamber 31, the upper half of which is of less diameter than that of the lower half previously mentioned for a purpose presently described.

A cup-forming die 32 is secured to the lower end of the boss 30 by means of a clamping bolt 33 extending centrally through said boss and having its lower end threaded and engaged in a threaded aperture in the die 32 which is held against rotation relatively to said boss by a key or pin 34, as shown in Figures 5 and 9.

The external diameter of the die 32 is equal to 20 the interior diameter of the cup-shaped portion of the cap 1 formed thereby but is of somewhat less diameter than that of the interior of the mouth of the bottle.

A sleeve 35 is reciprocally movable within the chamber 31 around the post 30 and die 32, the upper end of the sleeve being reduced to about the same diameter as that of the boss while the lower end is enlarged to about the same diameter as that of the interior of the lower half of the member 28.

The interior diameter of the remaining portions of the sleeve are substantially the same as the external diameter of the die 32 so that the dies and boss and also the interior walls of the lower half of the chamber 31 serve to guide the sleeve in its vertical movement, said sleeve being held against angular movement relatively to the member 28 by means of a key 36, Figure 9.

The member 28 extends downwardly from its supporting plate 7 some distance below the lower face of the cupping die 32 and has its lower end reduced and threaded externally and engaged by an internally threaded shearing member 37 of the same external diameter as that of the member 28 and also of about the same external diameter as the internal diameter of the lower shearing ring 22 with which it is adapted to cooperate for cutting a circular blank from the sheet material A preparatory to forming the cap, shown in Figures 1, 2 and 3.

The upper shearing ring 37 is also preferably made of hardened steel and is provided with peripheral recesses 37' for receiving a spanner wrench or equivalent by which it may be tightened and loosened when assembling or disassembling the parts of the upper cap-forming dies.

The portion of the shearing ring 37 below the lower end of the member 28 is provided with a concave annular groove 38 in which is seated the outer periphery of a circular coil spring 39, the inner periphery of which extends slightly beyond the inner face of the adjacent end of the member 28 and is of about the same or slightly less diameter than the external diameter of the post 8.

That is, the coil spring 39 is loosely seated in the annular groove 38 so that it may turn more or less freely therein and is held against displacement therefrom under its own tension, it being understood that the helixes of the spring will be arranged in close proximity to each other, particularly at the inner side of the coil for rumpling the skirt of the bottle cap during the cap-forming operation.

It will be noted upon reference to Figure 5 that the lower end face of the ring 37 is beveled upwardly and inwardly and that the coil spring 39 projects inwardly beyond the lower wall of the 5 groove 38 while the upper edge of the spring abuts against the lower end face of the member 28 to cooperate with the lower wall of the groove 38 in holding the spring against vertical displacement.

10 The inwardly protruding portions of the coil spring 39 serve as a stop for engaging the lower end of the sleeve 35 and thereby limiting the downward movement of said sleeve when the upper set of dies is raised to its normal position 15 so that the lower end face of the sleeve 35 will normally be disposed in about the same horizontal plane as the lower end face of the member 28 and upper face of the coil spring 39, as shown in Figure 5.

20 The lower end face of the sleeve 35 is provided with a multiplicity of relatively small substantially hemi-spherical recesses 40 for receiving a corresponding number of hardened metal balls or bearing members 41, the recesses and balls 25 being arranged in uniformly spaced relation circumferentially a slightly greater distance from the axis of the sleeve 35 than the balls 13, but in relatively close proximity to each other at the lower outer corner of the sleeve.

30 The number of balls 41 and recesses 40 corresponds to the number of balls 13 in the upper end of the post 8, but are arranged in opposed but slightly offset radial relation to those of the other set as shown in Figure 9, to facilitate the 35 corrugation of the rim 2 of the cap 1 and thereby to form the ribs 4 and grooves 5 in a manner hereinafter described.

The length of the arcs of each of the sockets 40 is slightly greater than half the circumference of each of the balls so that after the balls have been placed in operative position in said sockets the inner walls thereof may be crimped or swaged inwardly to hold the balls in their operative positions with their lower portions projecting slightly beyond the lower end face of the sleeve 35.

A collar 42 is slidably mounted upon the periphery of the lower portion of the cup-shaped member 28 for relative vertical movement thereon and is provided with vertically elongated slots 43 for receiving radial guide pins 44 which are screwed into the adjacent sides of the member 28 for holding the collar against angular movement relatively to the member 28 while permitting its free vertical movement.

This collar normally extends downwardly a short distance below the lower end face of the shearing ring 37 and is adapted to cooperate with the upper face of the shearing ring 22 for holding the sheet material in fixed position during the shearing cooperation of the ring 37 with the shearing ring 22.

The upper ends of the slots 43 are closed to cooperate with the pins 44 for limiting the downward movement of the collar 42.

Suitable guide rods 45 are secured to the plate 7 to extend downwardly therefrom at opposite sides of the member 28, the lower ends of said rods being extended through registering 70 apertures 46 in the upper end of the collar to assist in guiding the latter in its vertical movement.

Suitable coil springs 47 are interposed between the upper end of the collar 42 and lower face of 75 the plate 7 around the rods 45 for yieldingly

holding the collar in its extreme downward position, as shown in Figure 5.

The lower end of the cupping die 32 is provided with a multiplicity of vertically elongated peripheral slots 32', Figures 5 and 7, arranged in uniformly spaced circumferential relation corresponding to the spacing of the balls 41 for receiving the inner ends of the ribs 4 of the bottle cap 1 as the central portion thereof is depressed by the die 42 into the upper end of the opening 16 in the top of the lower die post 8, as will be hereinafter more fully described.

Operation

Assuming that the plunger plate 7 and dies 15 carried thereby are in their normal positions with relation to the lower die-supporting frame, as shown in Figures 5 and 6, and that the sheet metal from which the caps, shown in Figures 1, 2 and 3, are to be formed is fed across and upon 20 the upper face of the upper frame member 6' to the position shown by dotted lines in Figure 6.

The plunger plate 7 and parts carried thereby are then moved downwardly until the lower end of the collar 42 engages the upper face of the 25 sheet A to clamp and to temporarily hold the sheet in position to be cut upon the upper face of the ring 22.

Immediately following this engagement of the 30 lower end of the yielding collar 42 with the sheet material, the continued downward movement of the plunger plate 7 will bring the cutter ring 37 into shearing engagement with the lower shearing ring 22 for cutting a circular disk from the sheet material of the same diameter as the 35 internal diameter of the shearing ring 22.

Simultaneously with this cutting operation, the 40 pressure of the downwardly moving shearing ring 37 and coil spring 39 upon the marginal edge of the disk will bend said marginal edge downwardly 45 around the outer faces of the balls 13, at the same time depressing the sleeve 24 against the action of its retracting spring 27.

Then, as the downward movement of the upper 50 set of dies continues, the collar 42 will be yieldingly held in its clamping position by means of the springs 47 against the upper face of the lower cutter ring 22 so that after the cutting operation just described, the downward bending of the marginal edge of the previously cut disk will continue 55 through the engagement of the inner face of the coil spring 39 therewith and before the lower end of the die 32 has been brought into engagement with the previously cut disk, thus leaving the remaining portions of the disk in a flat horizontal plane, Figure 11.

As previously stated, the annular coil spring 39 is free to roll in its annular bearing 38 with more or less irregularity throughout its length, the 60 effect of which is to rumple the downwardly turned skirt portion of the disk around the upper end of the post 8 in that the wrinkles or crinkles will be formed by the inner sides of the numerous helices of the coil spring which presses the skirt against the periphery of the post, it being understood that the inner sides of the coil spring 65 will be more or less compressed by reason of their engagement with said skirt during the descent of the plunger plate 7 and parts carried thereby.

The normal distance between the lower face of the upper die member 32 and horizontal center of the spring 39 is greater than the depth of the skirt 3 of the finished bottle cap so that as the plunger plate 7 with the dies thereon continue their downward movement, or at about the same time that 70

the spring 39 passes beyond the lower edge of the previously down-turned skirt portions 3, the die member 32 will engage and depress the central portion of the disk into the upper end of the opening 16 and against the upper face of the cushion 17, thereby drawing the skirt upwardly and inwardly between the opposed sets of balls 13 and 41 to form the ribs 4 and grooves 5 which ribs will then extend across the rim 2 and downwardly along the inner sides thereof to points near the bottom 1' of the cup-shaped portion of the disk, as shown more clearly in Figure 3, thus completing the formation of the bottle cap as shown in Figures 1, 2 and 3.

15 After the bottle cap has been formed in the manner described, the plunger plate 7 with the dies thereon will be elevated to their normal up positions, as shown in Figure 5, thus permitting the sleeve 24 to be returned upwardly to its starting position by its springs 27 for stripping or ejecting the finished bottle cap from the top of the post 8 during which operation the collar 42 will be returned downwardly to its lowermost starting position by the springs 47 while the upper die sleeve 25 35 will be returned to its normal down position by its own weight or by other means, if required, the apparatus being then in position for a repetition of the operation described for forming other similar caps.

23 The lower end of the skirt of the cap will then be in the opening in the sheet material from which the bottle cap disk was previously cut and, as the sheet is again moved to register another portion thereof with and between the opposed sets of dies, the finished cap will be carried forwardly therewith to one side of the dies where it is free to drop through the opening onto the head of the bottle to be capped or may be removed by hand or otherwise for subsequent placement upon the head of the bottle preparatory to sealing the same thereon by a suitable capping machine, not shown.

When the finished bottle cap has been placed upon the head of the bottle in any manner with its cup-shaped portion in the mouth thereof and its skirt portion surrounding the head and adjacent portion of the neck of said bottle, the peripheral walls of the cup-shaped portion will be expanded against the walls of said mouth 50 while the skirt portion will be compressed against the outer periphery of the head and neck to firmly hold the cap in place against accidental displacement and at the same time to form a liquid-tight and air-tight joint with the bottle, it being understood that the bottom of the skirt will then be compressed around the neck of the bottle just below the bead or roll on the head thereof.

Any suitable capping machine or other means may be employed for applying the finished cap to and sealing it upon the head of the bottle in the manner described, and it is to be understood that the present invention relates to the construction of the cap and the method of and apparatus for making the same including any equivalents thereof irrespective of the means for applying the finished cap to the bottle except insofar as disclosed.

It will be noted upon reference to Figures 9 and 11, that the balls 41 project slightly below the lower end face of the die sleeve 35 to form an annular space so that when the dies are closed upon the cap in the act of forming the ribs 4 and grooves 5, the upwardly projecting radial ribs may be readily drawn into and through said space while the lower faces of the grooved por-

tions are free to move across and upon the upper end face of the lower die 8.

What I claim is:

1. In an apparatus for making bottle caps from sheet material, means including a collar for cutting a circular disk from said sheet, and means including a coil-spring ring co-axial with said collar for bending the marginal edge of the disk axially to form a skirt.

10 5

2. In an apparatus for making bottle caps from sheet material, means for cutting a circular disk from said sheet, means including a coil-spring ring for bending the marginal edge of the disk axially to form a skirt, and means for depressing the central portion of the disk 15 into cup-shaped form.

20 20

3. In an apparatus for making bottle caps from sheet material, means for cutting a circular disk from said sheet, a circular die having a multiplicity of rounded bearing members on one end near the periphery thereof, said bearings being arranged in uniformly spaced relation about the axis of the die for supporting the disk co-axial with the die, and means including a resilient ring co-axial with said axis for bending the marginal edge of the disk axially against said members.

25 30

4. In an apparatus for making bottle caps from sheet material, means for cutting a circular disk from said sheet, a circular die of less diameter than the disk for supporting the disk coaxial therewith, and means including a coil spring ring co-axial with said die for bending the marginal edge of the disk axially around and against the periphery of the die to form a rumpled skirt.

35 40

5. In an apparatus for making bottle caps from sheet material, means for cutting a circular disk from said sheet, a circular die for supporting the disk co-axial with the die, means for bending the marginal edge of the disk axially around the die, means for pressing the central portion of the disk axially into cup-shaped form, and means for corrugating the side walls of the cup during the cupping operation.

45 50

6. In an apparatus for making overall bottle caps from disks of sheet material, a die having one end provided with a multiplicity of bearings arranged in uniformly spaced relation about the axis thereof for supporting a disk co-axial therewith, and means including a resilient ring co-axial with said axis for pressing the marginal edge of the disk against said bearing members and around the periphery of the die.

55 60

7. In an apparatus for making overall bottle caps from disks of sheet material, a die having one end provided with a multiplicity of bearings arranged in uniformly spaced relation about the axis thereof for supporting a disk co-axial therewith, and means for pressing the marginal edge of the disk against said bearing members and around the periphery of the die, said means including a coil spring ring for engaging the marginal edge of the disk as it is pressed around the periphery of the die.

65 70

8. In an apparatus for making bottle caps from sheet material, co-axial dies relatively movable toward and from each other and having their adjacent ends provided respectively with bearing members arranged about the axis thereof at different radial distances from said axis, and a coil spring ring mounted on one of the dies co-axial therewith and a distance from said axis greater than that of the bearing members from the same axis.

9. In an apparatus for forming a bottle cap from a disk of sheet material, the combination of cooperative male and female dies relatively movable axially and between which the disk is placed, the female die having a cylindrical bore for receiving the male die, a disk-engaging member projecting inwardly beyond the walls of the bore around the axis thereof for pressing the marginal edges of the disk around and upon the 5 adjacent end of the male die when the dies are brought together to form the skirt of the cap, the relative axial movement of the dies being sufficient to carry said member beyond the end of said skirt after the skirt is formed, and means 10 for cupping the central portion of the disk while said member is still beyond the end of the skirt to allow said skirt to move axially of the male die without friction with said member during the 15 cupping operation.
10. In an apparatus for forming a bottle cap from a disk of sheet material, the combination of cooperative male and female dies relatively movable axially for pressing the marginal edges of the disk around and upon the adjacent end 20 of the male die when the dies are brought together to form the skirt of the cap, means for cupping the central portion of the disk and means for corrugating the portions of the disk between the cupped portion and skirt portion during the cupping operation.
11. In an apparatus for forming a bottle cap from a disk of sheet material, the combination of co-axial holding dies relatively movable axially and between which the disk is placed, said dies being adapted to engage opposite faces of the 25 disk under yielding pressure when the dies are brought together, means for pressing the marginal edges of the disk axially around one of the dies to form a skirt, and means for cupping the central portion of the disk after the skirt has been formed.
12. In an apparatus for forming a bottle cap from a disk of sheet material, co-axial male and female dies relatively movable axially for receiving the disk between them, the female die having a cylindrical bore for receiving the male die and provided with a rounded member projecting inwardly beyond the walls of the bore around the axis thereof for engaging and bending the marginal edge of the disk around the male die to 30 form the skirt of the cap, a holding die within the female die coaxial therewith and relatively movable axially therein, said holding die and male die being cooperatively arranged to engage opposite faces of the disk during the skirt-forming operation, means for cupping the central portion of the disk while the latter is engaged by the male die and holding die, and means for corrugating a portion of the disk during the cupping operation.
13. In an apparatus for forming bottle caps from sheet material, the combination of means for cutting a cap blank from said sheet, a forming die coaxial with said cutting means provided with a multiplicity of rounded bearing members about the axis thereof for supporting the blank coaxial with said die, and additional means arranged coaxial with the forming die and movable relatively thereto for pressing the marginal portion of the blank against said members and around the surface of said die.
14. In an apparatus for forming a bottle cap from a cap blank of sheet material, the combination of coaxial forming dies relatively movable toward and from each other, and between which the blank is placed, at least one of said dies being provided with a multiplicity of rounded bearing members about the axis thereof for supporting the blank coaxially with said dies, and additional blank forming means arranged coaxial with said dies and movable relatively thereto for pressing an intermediate portion of the cap blank against the bearing members and for drawing said intermediate portion of the blank across said members for corrugating the same.
15. In an apparatus for forming a bottle cap from a cap blank of sheet material, the combination of means for supporting the blank, and means arranged coaxially with the first mentioned means and movable relatively thereto for pressing the marginal portion of the blank around the surface of the first mentioned means, one of said means being provided with an uneven surface co-operating with the adjacent surface of the other means to form a rumped skirt during said relative movement.
16. In an apparatus for forming a bottle cap from a cap blank of sheet material, the combination of means for supporting the blank, separate means arranged coaxial with the first means and movable relatively thereto for pressing the marginal portion of the blank around the surface of said first mentioned means, one of said means being provided with a resilient uneven surface co-operating with the adjacent surface of the other means to form a skirt during said relative movement.
17. In an apparatus for forming a bottle cap from a cap blank of sheet material, the combination of means for supporting the blank coaxial therewith, separate blank forming means arranged coaxial with the first means and movable relatively thereto for pressing the marginal portion of the blank around the surface of said first mentioned means, said forming means having one of the co-operating surfaces thereof uneven or irregular, and the other surface smooth or regular, and one of said co-operating surfaces being resilient to form a rumped skirt during said relative movement.
18. In an apparatus for forming skirted bottle caps from a disk of sheet material, a die against which the disk is adapted to be supported coaxial therewith, forming means for yieldingly holding the disk against the die, means for bending the marginal portions of the disk around and upon the die to form the skirt, and means for cupping the central portion of the disk by drawing the portions engaged by the holding means inwardly toward said axis whereby said cupped portion is provided with an uneven expandible side wall.
19. In an apparatus for forming a skirted bottle cap from a disk of sheet material, a die against which the disk is adapted to be supported coaxial therewith, an axially movable holding die coaxial with the first die having bearing members spaced circumferentially around the axis thereof for engaging the disk, and means for forcing the marginal portions of the disk around and upon the first named die to form the skirt.
20. In an apparatus for forming a skirted bottle cap from a disk of sheet material, a die against which the disk is adapted to be supported and having its disk-supporting end provided with bearing members circumferentially spaced about the axis thereof, an axially movable holding die coaxial with the first named die for pressing the disk thereagainst and having its disk-engaging end provided with bearing members arranged in 75

- circumferentially spaced relation about the axis thereof, and means for engaging and forcing the marginal edges of the disk around and upon the first named die to form the skirt. 5
21. In an apparatus for forming a skirted bottle cap from a disk of sheet material, forming means operatively and yieldingly engaging the disk some distance from the center and outer edge thereof, means for bending the marginal portion of the 10 disk axially, and means for forcing the central portion of the disk axially and thereby drawing the portion engaged by the first means inwardly and forming said latter portion with an uneven expansible wall. 15
22. In an apparatus for forming a skirted bottle cap from a disk of sheet material, the combination of cooperating male and female skirt-forming dies adapted when brought together to press the marginal edge of the disk around and upon 20 the male die to form the skirt and to cause said dies to release their pressure upon the skirt after the latter has been formed, and means for cupping the central portion of the disk after the skirt has been released from the pressure of the 25 dies. 25
23. In an apparatus for forming a skirted bottle cap from a disk of sheet material, a die of less diameter than the disk and provided with bearing members in spaced relation about its axis for 30 supporting the disk coaxially therewith, means for bending the marginal portion of the disk axially around and upon the die beyond said bearing members to form the skirt, and means for forcing the central portion of the disk in 35 the same direction as the skirt and thereby to draw the portions of the disk engaged by said bearings inwardly. 35
24. In an apparatus for forming a skirted bottle cap from a disk of sheet material, coaxial male 40 and female dies relatively movable axially and between which the disk is adapted to be supported coaxial therewith, the male die being of considerably less diameter than that of the disk, an axially movable member cooperating with the 45 male die to yieldingly hold the disk coaxial therewith, means for bending the marginal portion of the disk around and upon the male die, and means for forcing the central portion of the disk axially and thereby to draw the portion of the 50 disk engaged by the male die and holding die inwardly. 40
25. In an apparatus for forming a skirted bottle cap from a cap blank of sheet material, the combination of coaxial holding dies relatively 55 movable axially and between which the blank is placed, at least one of said dies being provided with a multiplicity of bearing surfaces arranged about the axis thereof, blank forming means arranged coaxial with said dies, means for producing relative movement of the dies and said forming means for bending the marginal portion of the cap blank about said bearing surfaces and around the surface of one of the die members to form a skirt, and for moving said forming member 60 out of engagement therewith at the end of the forming operation to release the skirt, and additional means for producing relative movement of the cap blank and the bearing surfaces after the forming means has released the skirt for corrugating or wrinkling an intermediate portion 65 of the blank. 55
26. In an apparatus for forming a skirted bottle cap from a cap blank of sheet material, the combination of coaxial holding dies relatively 70 movable axially and between which the blank is placed, blank forming means arranged coaxial with said dies, means for producing relative movement of the dies and said forming means for bending the marginal portion of the cap blank to form a skirt, and for moving said forming means beyond the skirt out of engagement therewith to release the skirt, and additional means engaging an intermediate portion of the blank after the skirt has been released for corrugating or wrinkling said intermediate portion of the blank. 10
27. In an apparatus for forming a skirted bottle cap from a cap blank of sheet material, the combination of coaxial holding dies relatively 15 movable axially and between which the blank is placed, said dies having their adjacent ends provided respectively with bearing surfaces arranged about the axis thereof, means adapted to engage the blank for bending the marginal portion of said blank about the bearing surfaces of one of said dies to form a skirt and then to move out of engagement therewith to release the skirt, and additional means for drawing the blank between the bearing members after the skirt has been released for corrugating or wrinkling an intermediate portion of the blank. 20
28. In an apparatus for forming a bottle cap from a cap blank of sheet material, the combination of coaxial holding dies between which the blank is placed and relatively movable axially for 25 engaging opposite faces of the blank, at least one of said dies being provided with bearing surfaces arranged about the axis thereof, means comprising a forming element associated with one of the dies and movable relatively thereto for cupping the central portion of the blank whereby the portion of the blank adjacent the bearing surfaces will be drawn inwardly for corrugating said portions, said forming element being provided with recesses in the wall thereof for receiving said corrugations during the cupping operation. 30
29. In an apparatus for forming a bottle cap from a cap blank of sheet material, the combination of coaxial holding dies between which the blank is placed and relatively movable axially for 35 engaging opposite faces of the blank, cooperating means comprising a forming element and a recess adapted to receive said element associated respectively with said dies for cupping the central portion of the blank whereby the portion of the blank engaged, by the holding dies will be drawn inwardly, and means for corrugating said portion, one of said cooperating means being provided with recesses in the wall thereof for receiving said corrugations during the cupping operation. 45
30. In an apparatus for forming a bottle cap from a cap blank of sheet material, the combination of coaxial holding dies between which the blank is placed and relatively movable axially 40 for engaging opposite faces of the blank, at least one of said dies being provided with raised bearing surfaces arranged around the axis thereof adapted to engage an intermediate portion of the blank, and means for producing relative movement of the blank and said bearing surfaces when the dies are in holding engagement with the blank for corrugating or wrinkling a portion of the blank. 60
31. In an apparatus for forming a bottle cap from a cap blank of sheet material, the combination of coaxial holding dies between which the blank is placed and relatively movable axially for 65 engaging opposite faces of the blank, at least one of said dies being provided with raised bearing 70 surfaces arranged around the axis thereof adapted to engage an intermediate portion of the blank, and means for producing relative movement of the blank and said bearing surfaces when the dies are in holding engagement with the blank for corrugating or wrinkling a portion of the blank. 75

surfaces arranged around the axis thereof adapted to engage an intermediate portion of the blank, means for producing relative movement of the blank and said bearing surfaces, and means for maintaining said bearing surfaces in engagement with the blank under yielding pressure during said relative movement.

32. In an apparatus for forming a skirted bottle cap from a cap blank of sheet material, the combination of coaxial holding die members relatively movable axially and between which the blank is placed, at least one of said die members including a multiplicity of bearing surfaces arranged about the axis thereof and adapted to engage an intermediate portion of the blank, means adapted to engage the blank for bending the marginal portion of said blank about one of the die members to form a skirt, means for drawing the blank across said bearing surfaces for corrugating or wrinkling an intermediate portion thereof, and means for maintaining said bearing surfaces in engagement with the blank under yielding pressure during said corrugating operation.

33. In an apparatus for forming a skirted bottle cap from a cap blank of sheet material, the combination of coaxial holding die members relatively movable axially and between which the blank is placed, at least one of said die members including a multiplicity of bearing surfaces arranged about the axis thereof and adapted to engage an intermediate portion of the blank, means for producing relative movement of said die members to bend a marginal portion of the blank axially to form a skirt, means for drawing the blank across said bearing surfaces for corrugating or wrinkling an intermediate portion thereof, and means for maintaining said bearing surfaces in engagement with the blank under uniform yielding pressure during the forming of the skirt and said corrugations or wrinkles.

34. In an apparatus for forming a bottle cap from a cap blank of sheet material, coaxial dies relatively movable toward and from each other, and having their adjacent ends provided respectively with a multiplicity of bearing surfaces arranged about the axis thereof at different radial distances from said axis and adapted to engage an intermediate portion of said blank, and means for forcing the central portion of the blank axially and thereby drawing the portion of the blank engaged by the bearing surfaces inwardly and forming said central portion with an uneven expandible wall.

35. A device of the class described, comprising in combination, a die member, shearing means, means for actuating the shearing means to cut a disk from said sheet material and to bring the disk into operative relation with the die, resilient

means carried by the shearing means and actuated thereby for yieldingly bending a portion of the disk axially around and upon the die, and additional means for removing the formed disk from the die and releasably supporting the same in the disk opening formed in the sheet material to be removed by said sheet material from the vicinity of the die and shearing means, as a fresh portion of sheet material is brought into operative relation with said shearing means.

36. A device of the class described, comprising in combination, a die member, shearing means, means for actuating the shearing means to cut a disk from said sheet material and to bring the disk into operative relation with the die, means for bending a portion of the disk axially around and upon the die, and additional means for removing the formed disk from the die and releasably supporting the same in the disk opening formed in the sheet material to be removed by said sheet material from the vicinity of the die and shearing means, as a fresh portion of sheet material is brought into operative relation with said shearing means.

37. A device of the class described comprising in combination, a die member, shearing members associated with the die member having relative axial movement for receiving sheet material therebetween, means for producing relative axial movement of the shearing members to cut a disk from said sheet material, a coil spring ring connected with one of the shearing members having a normal interior diameter not greater than the exterior diameter of the die and actuated by said shearing member for bending a portion of the disk around and against the periphery of the die, and additional means for removing the formed disk from the die and releasably supporting the same in the disk opening formed in the sheet material to be removed by said sheet material from the vicinity of the die, and shearing means, as a fresh portion of sheet material is brought into operative relation with said shearing means.

38. A device of the class described, comprising in combination, a die member, shearing members mounted co-axially with the die member adapted to receive sheet material therebetween, a coil spring ring rotatably connected with one of the shearing members having a normal interior diameter not greater than the exterior diameter of the die, and means for producing relative axial movement of the shearing members and the die to first cut a blank from said sheet material and then move the coil spring ring axially over the marginal portions of the disk in rolling engagement therewith for bending the same around and upon the die.

CHARLES A. MacCORDY.
